UNITED STATES PATENT OFFICE.

OSCAR FALKENWALDE, OF BALTIMORE, MARYLAND, ASSIGNOR OF ONE-HALF TO OSCAR TESCHNER, OF BALTIMORE, MARYLAND.

WATER-GAS BURNER.

1,248,835.

Specification of Letters Patent. Patented Dec. 4, 1917.

Application filed January 3, 1917. Serial No. 140,395.

To all whom it may concern:

Be it known that I, OSCAR FALKENWALDE, a citizen of the United States, residing in the city of Baltimore and State of Maryland, have invented certain new and useful Improvements in Water-Gas Burners; and I do hereby declare the following to be a full, clear, and exact description of the invention, such as will enable others skilled in the art 10 to which it appertains to make and use the same.

The invention relates to a water gas burner.

The object of the present invention is to 15 improve the construction of hydrocarbon burners and to provide a simple, practical and efficient water gas burner of strong, durable and inexpensive construction designed for use in furnaces and various other places 20 and equipped with means for simultaneously vaporizing oil and water and causing a commingling of the same and discharging the mixture in a plurality of jets whereby the burner will develop intense heat at the 25 minimum cost.

A further object of the invention is to provide a burner of this character adapted to be easily primed and readily started and equipped with an automatic valve for controlling the inlet of the water to feed the same as required and prevent a flooding or excess of water when a gravity or other pressure feed is employed.

With these and other objects in view, the 35 invention consists in the construction and novel combination of parts hereinafter fully described, illustrated in the accompanying drawings and pointed out in the claims here-to appended; it being understood that various changes in the form, proportion, size 40 and minor details of construction, within the scope of the claims, may be resorted to without departing from the spirit or sacrificing any of the advantages of the invention.

45 In the drawings:

Figure 1 is a side elevation of a burner constructed in accordance with this invention.

Fig. 2 is a vertical sectional view of the 50 same.

Fig. 3 is a horizontal sectional view on the line 3—3 of Fig. 1.

Fig. 4 is a reverse plan view of the super-imposed spider or casing.

55 Like numerals of reference designate cor-

responding parts in the several figures of the drawings.

In the accompanying drawings in which is illustrated the preferred embodiment of the invention, the water gas burner comprises in its construction a base 1 constructed of suitable metal and preferably concavo-convex and provided with a marginal flange 2 curved upwardly and forming a peripheral groove and constituting the outer wall of the 65 base. The base is circular in plan view and its upper face may be provided with a lining 3 of more refractory material than the body of the base, which is adapted to operate as a combined starting cup and reflecting element. The upper face of the base is convex and presents an inclined surface and the oil which is adapted to drop upon the base in the starting of the device will run down the sides or inclined faces of the 70 base and collect in the marginal groove or gutter if the supply should be more or less excessive. This will prevent any of the oil from being wasted and will insure a burning of all of the oil used in starting the 75 burner.

The base is provided with a central opening 4 in which is secured a water conduit 5 illustrated in the accompanying drawings as consisting of a plurality of pipe fittings 85 and couplings and receiving an inner oil conduit 6 extending upwardly through the outer water conduit and forming an intervening water space or passage between it and the water conduit. A coupling 7 is connected with the lower end of the oil conduit and the water conduit is provided at the bottom with a T-coupling 8 forming a lateral connection for the water supply pipe 9.

The oil pipe and water pipe are designed 95 to be connected with suitable tanks or other sources of supply (not shown) and the feed may be by gravity or any other pressure. The outer water conduit is provided below the base with a lock nut 10 and it has a reducing nipple 11 located above the base and it is provided at the upper end with a valve seat 12. The base is firmly clamped between the reducing nipple 11 and the lock nut 10, a spacing sleeve 13 being interposed between 100 the lock nut and the lower face of the base, as clearly illustrated in Fig. 2 of the drawings.

The valve seat 12, which is beveled, is formed by the upper end of the reducing 110

nipple and the pipe section 14, and a valve 15, which is slidable on and guided by the upper portion of the oil pipe 6, coacts with the valve seat. The lower end 16 of the 5 valve is beveled to fit the valve seat and the said valve is composed of upper and lower sections, the upper section 17 being in the form of a reducing nipple and having an inner lining or packing 18 adapted to form 10 a practically water-tight connection between the valve and the upper guiding portion of the oil tube. The valve is maintained closed by gravity and the internal pressure of a drum 19 consisting of a casting and having 15 a lower threaded opening 20 for the reception of the reducing nipple 11 of the water conduit. The drum 19, which is divided by a horizontal plate or portion 22^a into upper and lower chambers or compartments 21 and 20 22, has an upper threaded opening 23 into which is screwed a tubular portion 24 of a hollow superimposed spider or casing 25 and the said oil tube extends into the spider and has its upper end arranged in spaced relation 25 with the inner face of the tubular portion 24 to provide an intervening space for the passage of the water or oil vapors. Also the partition 22^a is provided with a central opening 26 of slightly greater diameter than 30 the exterior of the oil tube to provide a central annular passage.

The drum is also provided with a series of vertical tubes 27 formed integral with the drum and extending from the top to the bottom thereof and providing vertical passages 28, which extends entirely through the drum and into which is discharged the mixture from the spider 25. The horizontal partition plate 22^a terminates at the tubes and 40 its periphery is spaced from the interior of the drum 19 to provide an outer opening or space 26^a which communicates with the upper and lower compartments of the drum. The drum is shown provided with five vertical 45 passages 28 and the spider consists of a central portion and five radially arranged arms 29 having depending nipples 30 provided with jet apertures 31 for discharging the combined oil and water gas into the vertical passages of the drum. The arms are provided with longitudinal openings 32 and are closed by removable plugs 33, when the 50 passages 32 are drilled. It is not necessary to clean the hollow spider or superimposed 55 casing, as the water gas is not burned at the nipples and carbon will not collect in the passages of the spider of casing. Also the water gas passing through the same will maintain the passages of the spider in a 60 clean condition and the spider will also operate to dry and heat the commingled vapors. The nipples 30, which are squared at their outer portions to receive a wrench, have threaded inner or upper portions 34 65 which are screwed into threaded openings

35 in the lower walls of the arms of the spider. The mixture is discharged downwardly from the jet apertures and it has been found by experience that it burns with an intense green flame. The drum becomes 70 enveloped in such flame and air to support and to enable the gas to be burned with practically complete combustion is fed to the flame through the base by vertical air tubes 36 having threaded lower ends 37 which 75 are screwed into openings 38 in the base. The base is preferably enlarged as shown around the openings and the air tubes, which become highly heated, extend above the plane of the bottom of the drum. 80

The spider forms a convenient priming device as the oil, when the full flow is turned on, will be discharged from a tip or head 39 having openings 40 located opposite the passages of the arms of the spider. The 85 oil will then drip or flow from the nipples and will be discharged upon the plate or base. The oil on the base is then ignited and the burner started. After the burner is started the flow of oil is cut down and instead of discharging into the passages of the spider and jet it will ooze or discharge slowly from the openings 40 and flow down the oil pipe or tube exteriorly of the same into the drum and will mix or float upon the 90 water contained therein and the heating of the drum will cause the boiling of the liquid contents thereof and a vaporization of both the oil and water, the horizontal plate or partition operating as a heating element to 100 assist in vaporizing the oil and water. The commingled vapors or gases resulting from the boiling of the oil and water will under the pressure created in the drum by the heating of the contents thereof pass upward and 105 enter the superimposed casing or spider and discharge at the nipples thereof. The gas discharged from the nipples burns at the lower portion of the drum where it mixes with the hot air from the air tubes 36, producing an intense heat which may be varied by controlling the flow of oil to the burner. It has been found in practice that the pressure within the drum acting on the valve maintains the latter in a closed position during a portion of the time and when the pressure is decreased through the consumption of the gas the valve will open under the pressure of the water and permit a quantity of water to enter the drum. When the 115 burner is running steadily the valve opens and shuts in comparatively rapid succession. Also in practice suitable valves (not shown) will be employed for controlling the flow of water and oil to the burner. The superimposed hollow spider or casing may consist of a casting or be constructed in any other desired manner and the threaded portion or neck 24, which is screwed into the top of the drum is locked to the same by a 120 125 130

- lock nut 41. Suitable gaskets or packings may be employed where required to produce a steam-tight or water-tight joint or connection.
5. What is claimed is:
1. A burner of the class described including a drum, a water conduit connected with the drum, a casing located above and communicating with the drum, an oil pipe communicating with the drum, and means located within the drum for automatically controlling the supply of water to the same.
  2. A burner of the class described including a drum, a superimposed casing having a passage communicating with the drum, said casing being also provided with outlets directed toward the said drum, a water conduit extending to and communicating with the drum and provided with means for automatically controlling the supply of water to the said drum, and an oil tube communicating with the casing and the drum and having a discharge nozzle of less diameter than the said passage to permit oil to flow back into the drum.
  3. A burner of the class described including a drum having air passages extending through it and provided with upper and lower compartments, a water conduit connected with the drum at the bottom thereof, a superimposed casing communicating with the drum at the top thereof, an oil pipe extending through the drum and into the water conduit and communicating with the drum and the casing, the latter being provided with jet apertures located opposite the passages of the drum, and a valve guided by the oil pipe for controlling the flow of water into the said drum.
  4. A burner of the class described including a drum provided with vertical tubular portions forming air passages, said drum being also provided with a partition dividing the drum into upper and lower compartments, a water conduit connected with the drum at the lower compartment, an oil conduit extending from the water conduit through the drum, a superimposed casing connected with the drum at the top thereof, said superimposed casing receiving the oil conduit and having jet apertures located opposite the air passages of the drum, and means for controlling the supply of oil and water.
  5. A burner of the class described including a drum provided with vertical tubular portions forming air passages, said drum being also provided with a partition dividing the drum into upper and lower compartments, a water conduit connected with the drum at the lower compartment, an oil conduit extending from the water conduit through the drum, a superimposed casing connected with the drum at the top thereof, said superimposed casing receiving the oil
  - conduit and having jet apertures located opposite the air passages of the drum, a base located beneath the drum and projecting outwardly beyond the same and adapted to receive oil to form a starting device, and means for controlling the flow of oil and water to the burner.
  6. A burner of the class described including a drum provided with vertical tubular portions forming air passages, said drum being also provided with a partition dividing the drum into upper and lower compartments, a water conduit connected with the drum at the lower compartment, an oil conduit extending from the water conduit through the drum, a superimposed casing connected with the drum at the top thereof, said superimposed casing receiving the oil conduit and having jet apertures located opposite the air passages of the drum, and a substantially concavo-convex base located beneath and extending beyond the drum and provided with an upwardly projecting marginal flange forming a groove or gutter.
  7. A burner of the class described including a drum provided with vertical tubular portions forming air passages, said drum being also provided with a partition dividing the drum into upper and lower compartments, a water conduit connected with the drum at the lower compartment, an oil conduit extending from the water conduit through the drum, a superimposed casing connected with the drum at the top thereof, said superimposed casing receiving the oil conduit and having jet apertures located opposite the air passages of the drum, a substantially concavo-convex base located beneath and extending beyond the drum and provided with an upwardly projecting marginal flange forming a groove or gutter, and air tubes mounted on the base and extending above the bottom of the drum.
  8. A burner of the class described including a drum provided with vertical tubular portions forming air passages, said drum being also provided with a partition dividing the drum into upper and lower compartments, a water conduit connected with the drum at the lower compartment, an oil conduit extending from the water conduit through the drum, a superimposed casing connected with the drum at the top thereof, said superimposed casing receiving the oil conduit and having jet apertures located opposite the air passages of the drum, a base connected with the drum at the bottom thereof and extending outwardly beyond the same and provided with openings, and air tubes mounted on the base at the said openings and extending above the bottom of the drum.
  9. A burner of the class described including a drum, a superimposed casing connected with the drum at the top thereof and

- provided with jet apertures, a base located beneath the drum, a water conduit extending through the base and the bottom of the drum and connecting the base to the drum, 5 said water conduit being provided at the upper end with a valve seat, an oil conduit extending through the water conduit and through the drum into the superimposed casing and communicating with the same to 10 form a priming device and with the drum to supply oil to the same, and a valve guided on the oil conduit and coacting with the valve seat to control the inlet of water automatically.
- 15 10. A burner of the class described including a drum, a superimposed casing connected with the drum, a water conduit extending to and communicating with the

drum, an oil tube or pipe extending into the drum, and a valve guided by the oil tube 20 for controlling the flow of the water to the drum automatically.

11. A burner of the class described including a drum, a water conduit connected with the drum for supplying water to the same, an oil conduit communicating with the drum for supplying oil thereto, and an automatic valve located within the drum and controlled by the internal pressure thereof for regulating the feed of water to the drum.
